UNITED STATES PATENT OFFICE.

MATTHEW R. MOORE, OF INDIANAPOLIS, INDIANA.

STEAM-ENGINE GOVERNOR.

SPECIFICATION forming part of Letters Patent No. 318,782, dated May 26, 1885.

Application filed October 13, 1884. (No model.)

To all whom it may concern:

Be it known that I, MATTHEW R. MOORE, of Indianapolis, Marion county, in the State of Indiana, have invented certain new and 5 useful Improvements in Steam-Engine Governors, of which the following is a specification.

My invention applies to that class of steam-engines in which the regulation is effected by 10 changing the position of an eccentric on the shaft, so as to give greater or less degree of eccentricity rightly conditioned to give a longer or shorter period of opening to admit steam to the cylinder at each stroke. Governors of this general class have been long 15 known. A. Kendall in a patent to him dated December 26, 1882, No. 269,678, shows such a governor actuated by the centrifugal force of weights carried around with the shaft and subject to the force of springs which tend to hold 20 the said weights inward. The connections are arranged togglewise, so as to work at great advantage in overcoming the resistance and shifting the eccentric outward or inward as 25 the variations in the speed due to changes in the load on the engine or in the pressure of the steam, or both, may require. I employ the same general arrangement in my present governor, and the balance between the centrifugal force 30 and the springs is the ultimate means of determining the speed at which the engine is allowed to run; but there is a difficulty in making such governors sufficiently quick and yet temperate in their action. There is a 35 tendency for the weights to stay inward until the speed has risen above the proper point, and then to move outward too far, feeling an increased centrifugal force as they move outward. Such movement induces a great change 40 in the position of the eccentric, cutting off the steam shorter. This causes the engine to run slow again, below the proper speed, and allows the weights to be brought inward by the force of the springs beyond their proper points. 45 This induces a repetition of the vibration. Such tendency to vibrate between high and low velocities has been overcome by myself and others by means of a cylinder having a loosely-fitted piston carried around with the 50 shaft and so connected to the weights or their changing parts that any sudden movement will be checked by the resistance of a fluid

contained in the cylinder. Such a device, sometimes termed a "dash-pot" or "cataract," offers great resistance of the fluid to 55 prevent the vibration referred to; but it also offers some resistance to the proper gradual changes required. It is expensive in construction. The oil or other liquid contained in the cataract is liable to escape. When air is used 60 as a fluid, a cataract does not exert sufficient force and with sufficient promptness unless large and cumbersome. I have discovered that an entirely different principle may be made available for this purpose, and have discovered 65 and practically applied means for carrying it into effect and checking the vibrations without cataracts and without detracting from the sensitivity of the governor. The weights yield to any change of speed and induce the desired 70 moderate changes in the position of the eccentric on the shaft without allowing sudden movements. The mechanism is withal very simple. For a single engine the shaft should have a 75 strongly and rigidly connected fly-wheel, which performs its ordinary functions. Besides and entirely independent of the ordinary fly-wheel, I employ a loose fly-wheel, which, with proper connections for controlling the valve, serves 80 as a governor by its momentum. I will, for brevity, term it a "dead-wheel." It is fitted 85 on a bearing revolved with the shaft and tied to the shaft by flexible mechanism. The gentle pull or push of the flexible mechanism serves, first, to revolve the dead-wheel; second, to allow the dead-wheel to drag a little behind or to run a little ahead of the shaft when the speed suddenly changes; and, third, to accelerate or retard the dead-wheel, so as to soon 90 bring it to the same speed as the shaft, whatever may be the rate of revolution of the latter. This loose fly-wheel or dead-wheel is so connected with the eccentric that when the shaft commences to run slower or faster than the dead-wheel the change of relation changes 95 the position of the eccentric on the shaft. I can use this dead-wheel alone as a governor. To thus use it, I so arrange the connections that when the engine runs too slow the dead-wheel gets ahead of the shaft by simply revolving a 100 little faster than the shaft, and thus causes the steam to follow the piston farther, thus increasing the power of the engine to overcome the resistance, and causing it to run faster, so as to

catch up with the dead-wheel and again run in harmony with it; and when the shaft gets ahead of the dead-wheel, indicating that the engine is running too fast, the governor will 5 so change the mechanism as to cut off the steam shorter, thus reducing the velocity of the engine until it is again in harmony. The dead-wheel will increase its speed gradually during any period while the shaft runs ahead 10 of it, and will decrease its speed gradually during any period while it runs ahead of the shaft; but its speed will approximate uniformity. It will be understood that in such mode of working some means should be employed 15 in the act of starting for turning the dead-wheel actively by hand, or temporarily clamping the dead-wheel to the shaft, or for otherwise suspending the action of the governor, as otherwise the turning of the shaft 20 faster than the dead-wheel, which must necessarily occur under such conditions, will cause the supply of steam to be cut off, and the speed can never be properly raised; but after the speed is once raised such a governor may take 25 care of it so far as to avoid sudden changes of velocity. Slight supervision by an attendant, who may give an occasional touch of the hand to prevent a gradual increase or decrease of speed is sufficient to secure good regulation 30 by this means. I will not enter further into the details of so working, because I do not propose in general to thus use the invention. In what I esteem the best means of carrying out the invention I employ this governor 35 in combination with a centrifugal governor, the whole carried around on the shaft. In such combination the centrifugal governor may be considered the principal agent, and the dead-wheel, acting by its momentum, may 40 be considered only an auxiliary. Weights and springs are mounted on the shaft subject in the ordinary way to the varying centrifugal force, except as their effect is influenced by my dead-wheel. I may call the dead-wheel 45 and its connections a "momentum governor," considered with reference only to the effects of the momentum of the dead-wheel and its associated parts under sudden changes of speed. I combine a momentum governor with a centrifugal governor.

The following is a description of what I consider the best means of carrying out the invention.

The accompanying drawings form a part of 55 this specification.

Figure 1 is a side elevation showing a portion only of the mechanism. Fig. 2 is a corresponding central cross-section. The remaining figures show the mechanism complete. Fig. 3 is a side elevation showing the governor running with a short cut-off. Fig. 4 is a nearly central section. It is a section on the line $x-x$ in Fig. 5. Fig. 5 shows the parts in the act of the engine being reversed. Fig. 6 shows the governor with the parts fully reversed and the engine working successfully, turning in the opposite direction.

Similar letters of reference indicate corresponding parts in all the figures where they occur.

A is my loose or dead wheel, certain portions of which will be designated when necessary by additional marks, as A' A'' . As the dead-wheel A is intended to be effective entirely by its inertia, it is important that it 75 have considerable mass. It is also obviously important for high speeds that the mass of the dead-wheel and of its attachments be distributed symmetrically so as to balance. There may be as many arms A^3 as required connecting the rim A^2 with the hub A' . On the inner face of the wheel A are formed two peculiarly-shaped cams or partial internal flanges, A^4 A^5 . They present approximately volute outlines, 80 reversed the one relatively to the other, as 85 shown.

C is the shaft of the engine which it is the object of the device to regulate. It will be understood that there is a crank, piston, cylinder, and other essential parts of a steam-engine, and that the valve and parts are so proportioned and arranged that the point in each stroke to which the piston has traveled when the further admission of steam to the cylinder is stopped, or what is sometimes known as the 95 "point of cut-off," may be varied within wide limits by properly varying the throw of the valve.

C' is an arm rigidly keyed or otherwise fixed on the shaft.

C² is a central boss or bearing, which forms a nearly-frictionless bearing for the dead-wheel A.

D is a shifting eccentric. It will be understood that it is encircled by a strap, (not 105 shown,) which as the eccentric revolves operates the valve through an eccentric-rod. The eccentric is provided with an arm, D', which is connected to the arm C by a pivot or rivet at D¹. The shaft C extends through a curved 110 slot, d, in the eccentric, allowing the eccentric to be shifted thereon. In the middle position it gives no steam or but very little to the cylinder. When shifted so that the shaft C is received in one end of the curved slot d, the 115 valve is operated to go ahead with full steam, and when the eccentric is shifted so that it holds the shaft C in the other end of the curved slot d the parts are in condition for working backward with full steam. When it is in intermediate positions, it operates the valve properly for going ahead or going backward with less steam, or cutting off the steam shorter. The eccentric D is provided with arms D² D³, carrying anti-friction wheels d² d³, which apply against the inner surfaces of the cams A⁴ 120 A⁵, one wheel, d², against the cam A⁴, and the other wheel, d³, against the cam A⁵. When, by virtue of its inertia under varying speeds, or when by any other cause, the loose fly-wheel 125 or dead wheel A shifts its position forward or backward relatively to the shaft C, it changes the relation of the cams A⁴ A⁵ to the anti-friction wheels d² d³, and shifts the eccentric D in 130

one direction or the other, turning on its pivot D^4 . The forms given to the cams $A^4 A^5$ are so related to the arms $D^2 D^3$ that the dead-wheel A may shift forward or backward, and 5 the wheels $d^2 d^3$ will just make a fair contact with their respective cams $A^4 A^5$, and each change of the shaft C forward or backward relatively to the dead-wheel A will set the eccentric nearer to or farther from its middle or 10 neutral position, thus giving an earlier cut-off in one case and a later cut-off in the other. It will cut off shorter when the shaft gets ahead of the steadily-turning dead-wheel, and will follow farther when the shaft gets behind 15 it. Two weights, B , are pivoted on the interior of A at points b opposite to each other.

1 I are springs abutting against bearings a^3 a^3 on two of the arms A^3 , and exerting their resilient force on the weights B B through 20 rods H H , pivoted to B B at $b^2 b^2$. These springs tend to draw the weights inward against the centrifugal force due to the revolutions which tends to drive them outward.

2 E are links, each connecting between a pivot, 25 b' , on a weight B and a pivot, c^3 , set in a boss, C^3 , on the side of the shaft C . By turning the nuts H' H' the force exerted by each spring I to draw inward the connected weight B can be varied. It will be seen that, as in centrifugal governors generally, the centrifugal 30 force of the weights B tends to turn them on their pivots b and cause them to lie quite out against the interior of the wheel A . The springs I , on the contrary, acting through the 35 rods H , draw the weights B inward toward the shaft C . The tension of the springs is so adjusted that when the engine is working at just the proper rate the weights B will stand in an intermediate position. Thus conditioned any 40 increase in the speed of the engine will result in causing the centrifugal force of the weights B to overcome the tension of the springs I and move the weights outward with the effect to shift the eccentric D , so as to give less 45 steam, and any decrease in the speed will allow the springs to overcome the centrifugal force and bring the weights inward with the effect to cause the steam to follow farther. The pieces B constitute links, which with the 50 links E make toggle-connections between certain points b on the dead-wheel and the side bosses, C^3 , on the shaft. These toggles communicate force gently between the shaft and the dead-wheel.

55 The operation will be readily understood. The parts, having revolved a sufficient time to acquire easy positions, remain in the same relative positions and revolve without effect so long as the speed of the engine is uniform; but 60 when, for any reason, the shaft commences suddenly to turn too fast the dead-wheel A falls behind. In other words, the shaft gets ahead of the dead-wheel. This movement acts through the angular position of the links E to 65 force outward the weights B against the force of their springs I . This force is in the same direction as the increased centrifugal force,

which commences at the same time or shortly after to be felt by the weights. The two kinds of governors, the momentum governor and the 70 centrifugal governor, each contributes to the effect, the momentum governor first and momentarily tending to make the action of the combined governors more prompt than the centrifugal governor alone, but the effect of the momentum governor is only momentary. As soon 75 as it has aided to urge the weights out to about the proper point its force is lost. The centrifugal governor ultimately controls and determines the exact speed to which the engine shall 80 again be brought and held. Correspondingly when the speed is partially arrested from any cause, if the arresting is sudden, such as results from a sudden attachment of additional machinery or running a thick log of hard 85 wood up to a saw, the momentum governor is of great effect to promote the promptness with which my governor will call for and receive more steam. The instant the shaft C commences to run slower the loose dead-wheel 90 A by its continuing to rotate at the former velocity exerts its momentum through the connection to the weights B , and through the links E to pull the weights B inward. This movement, which would soon after be effected 95 by the springs I in consequence of the reduction in the centrifugal force due to the diminished velocity, is hastened by the combination of the momentum governor therewith. This operation is important, and I may describe this 100 operation again in different words. The inertia of the heavy dead-wheel has a tendency to make it when in motion maintain a uniform speed. When an increase of load occurs, the momentary check given the engine is not directly communicated to it because it is loose on the shaft. It therefore tends to run ahead of the engine, thus adjusting the eccentric for the admission of more steam to meet the increase of load. If a diminution of load occurs, 105 the opposite result is reached, for then the relieved engine tends to jump ahead and leave the dead-wheel behind. This movement adjusts the eccentric for less steam. Thus the 110 inertia of the dead-wheel, weights, and springs 115 is all brought to bear to assist the centrifugal force of the weights or the elastic force of the springs whenever an adjustment for more or less steam is required. The action of the governor is such that it feels the first impulse of 120 change, and does not, like simple centrifugal governors, wait until a change of speed has been established before making its adjustment. There are further points which will 125 now be described.

P is a brake-strap, of leather, sheet metal, or other durable material, fastened to a fixed point at p , and to a short arm of a hand-lever, Q , which turns on a fixed center, q . This strap is of such length that when the lever is 130 adjusted in the position shown in strong lines, which is its usual position, it is of no effect. When it is desired to reverse the engine, the free end of the hand-lever is suddenly lifted,

tightening the strap P and throwing a sudden friction on the periphery of the dead-wheel A. If the engine is running with a high velocity, the sudden resistance thus imposed 5 on the dead-wheel, holding it back while the other parts are moving rapidly as before, will, by the momentum of the other parts, effect the required reversing. It will do this by forcibly bringing the links E into the positions shown in Fig. 6 and beyond it, approximating the condition shown in Fig. 7. This 10 reverses the engine. It is important to immediately afterward throw the hand-lever back into its original position, so as to set the dead-wheel free and allow it to revolve in its 15 new direction. This means of reversing applies well, whether the engine is previously revolving in one direction or the other.

I have devised means for effecting the reversing by throwing the dead-wheel forcibly 20 backward. The same means also serve for slowing or hastening. R is a hub, mounted loosely on the shaft alongside of the dead-wheel, equipped with arms R', having pins 25 R², which stand in considerable intervals provided between internal stops A⁶ in the dead-wheel. This hub R turns with the shaft and ordinarily stands in such position that its pins R² are not touched by the stops A⁶. The 30 dead-wheel has liberty to turn faster or slower than the shaft to a sufficient extent without being restrained or any way affected by the pins R². But there are provisions for forcibly turning the hub R partially around relatively to the shaft in either direction, no matter 35 how fast the shaft may be turning. When this is done in the direction to turn the dead-wheel backward, it slows the engine, and on being carried far enough effects the reversing. 40 When it is done in the opposite direction, it adjusts the eccentric to give steam longer and causes the engine to run faster. Such turning of the hub R relatively to the shaft is effected through a forked hand-lever, S, which takes 45 hold of trunnions on a ring, T, mounted in a sleeve, W, which latter is secured on the shaft by a feather, V, so that it is compelled to turn therewith, but is free to be moved endwise thereon. Slides w, fixed to the sleeve W and 50 traversing in spline grooves in the shaft, carry each a roller, X, received in spiral grooves r in the interior of the hub R. So long as these parts are left free they are of no effect; but when, with the shaft and its connections revolving 55 at any velocity whatever, the attendant seizes the lever S and moves the sleeve W endwise on the shaft the action of the rollers X in the spiral grooves r causes the hub R to turn forward or backward relatively to the shaft. 60 This by means of the arms R' and pins R² turns the dead-wheel A correspondingly forward or backward until it acts on the dead-wheel through the corresponding stop, A⁶. Turning it forward gives the engine more steam 65 and causes it to go faster. This may be useful in various exigencies. Moving the hand-

lever S in the opposite direction so as to turn the dead-wheel backward will give less steam and thus slow the engine and making the action vigorous, and carrying it far enough will not only stop it, but will carry the dead-wheel past the neutral point and reverse the engine. So soon as this is effected the hand-lever S 70 may be again liberated and the engine will work as before, but revolving in the reverse direction subject to the regulation of the governor. I can adjust the tension of the springs I and consequently the speed to which the engine will regulate under any given pressure of steam by turning the nuts H' in one direction 75 or the other. The rods H may be prolonged a little, and each may carry a jam-nut outside of the nut H' to aid in reliably securing these parts. I provide by slots d' of reasonable 80 length in the arms D² D³ and by any ordinary 85 or suitable means of confinement for changing the position of the pins on which the anti-friction wheels d² d³ are mounted. I can thus adjust the positions of said wheels to set the eccentric and compensate for imperfections in 90 the workmanship or for wear of the parts. I make the dead-wheel A in two parts or halves bolted firmly together. I also make the eccentric D in two parts, with provisions for 95 fixing the parts rigidly together. These provisions for separating and uniting the parts facilitate their application and removal when required. My means of adjusting the position of the eccentric offers some friction, notwithstanding the employment of the wheels d² d³, 100 but it is only a resistance against a change of eccentricity of the eccentric. The carrying around of the eccentric by the shaft is done by the pivot D connecting the arms C'D'. That is 105 done without friction. The considerable friction due to the holding the eccentric by the extended arms D² D³ is all a resistance simply to the changes of eccentricity. On this matter it should be remembered that there is a strain developed by the engine alternately in 110 opposite directions by working the valve, which is more than sufficient to overcome such friction. The tendency of the resistance of the valve to alter the throw of the eccentric 115 changes its direction four times in each revolution. From the beginning of the travel in either direction to mid-stroke the tendency is to increase the throw; from mid-travel to the end to diminish it. When at the turning points and at mid-travel, the effect is nil. In my governor this tendency cannot really move the eccentric, but jams it against the cams, so that the friction locks it in position. The changes caused by the weights and springs, aided by the momentum of the dead-wheel, can take 120 place only when the eccentric is passing through those neutral points. At high speed these occur some forty times per second. This is sufficiently often to permit regulation. The locking between these times prevents the 125 changes from going too far. The act of adjustment will be a series of very short ap-

proaches toward the proper position, instead of vibrations about it, as in the former style of governor.

There is another mode of working my invention, which is of advantage when it becomes particularly important to avoid vibrations of speed rather than to secure prompt regulation. In such the momentum governor does not, when the speed becomes too high or too low, contribute to effect the changes of position of the eccentric, but, on the contrary, exerts its force momentarily to prevent such changes. To attain this condition, all the parts may be exactly as shown, but with the motion in the reverse direction—the opposite of that shown by the arrows. Thus adjusted, the momentum governor pulls against instead of with the centrifugal governor; but the momentum governor must not be of so much force as to overrule. In this opposition mode of working, when resistance is suddenly removed and the shaft turns too fast, the centrifugal members of the combination, as usual under such conditions, call for less steam. The dead-wheel is connected the reverse of the one above described, so that the shaft, by getting ahead of it, tends to induce a change not in the same direction, as before described, so as to also call for less steam, but, on the contrary, to induce a change in the opposite direction, so as to call for more steam. The dead-wheel, therefore, instead of making the change of steam-supply greater with any given change of speed, tends to make a change in the opposite direction, and thus, in fact, exerts its force to prevent any change of steam-supply. The conflict tends to keep the point of cut-off at the same point as before. It tends apparently to defeat the regulation; but the effect of the inertia of the dead-wheel is only momentary. The considerable friction due to the bearing and the pull or push due to the connections soon accelerates or retards the dead-wheel and brings it to the new speed of the shaft. So soon as this occurs all the opposition which the inertia of the dead-wheel has opposed to the centrifugal governor is withdrawn, and the mechanism slowly yields to the more persistent force of the centrifugal governor. In all cases the combination, if properly adjusted, brings the engine to the same speed and holds it there, whether the steam be high or low, so long as the steam-pressure is sufficient, and whether the load be small or great, so long as the load is not beyond the power of the engine with the pressure available. There are no cataracts to keep filled with oil. There is no appreciable wear.

I attach importance to the curved path in which my eccentric is shifted. If a governor is so constructed that the eccentric moves across the shaft in a straight line, it may be so applied to the engine as to give a constant lead—that is, the valve-opening when the engine is passing dead-centers will be the same, whether the engine be using full steam or cutting off short, and this has been claimed as an advantage possessed by that construction.

I think, however, that constant lead is not best. When the engine is fully loaded and using steam up to the maximum power—say, three-quarters of the stroke—compression is small, and a liberal amount of lead is necessary to enable the engine to pass centers smoothly, as well as to give early enough valve-openings to secure prompt admission and a good steam-line; but when cutting off short, compression is high, and takes the place of steam-lead to such an extent that little or none is necessary. Besides, if we have constant lead the valve never can entirely stop admission, it will always open to the extent that the lead exceeds the lap when passing centers, and hence the speed of the engine when running light cannot be perfectly controlled. The speed will also be affected by changes in the steam-pressure.

My governor with its curved motion in changing has a diminishing lead, giving as much as I want at full-stroke, and little or none when cutting off short. This is done by so proportioning the eccentric that when it is giving the valve its shortest travel it simply moves it the extent of its lap or from one port to the other without opening at all. I can then regulate the amount of lead given at longest travel by the angular advance of the eccentric. This maximum lead will diminish to nothing when at shortest travel. Such valve is capable of stopping the admission of steam entirely when conditions require, and the governor will adjust itself so that the speed will not be appreciably affected by variations in the steam-pressure. With the ordinary construction having the parts so adjusted, if we should reverse the engine by moving the eccentric by any means across to the other side of the shaft, we would find that our angular advance becomes an advance backward, and our lead an increasing lead. To work successfully with such plan, we should have to change the position of the governor on the shaft. This might be done by having two keyways in it to make it reversible; but in my construction I take advantage of the curve in which the eccentric moves to get a diminishing lead on each side without moving the governor on the shaft. I can make the amount of curvature and of lead what I will by varying the length of the arms C' D'. I provide a slot in the arm C' and a corresponding slot in the arm D', and employ in each slot an adjustable center, D⁴, which may be shifted upward or downward in the slots and be tightened in any position to form a pivot on which the eccentric may turn. Shifting the center D⁴ inward toward the center of the shaft C and securing it in such position increases the curvature of the path followed by the center of the eccentric as its eccentricity is changed. In reversing the engine the brake-lever Q and the controlling-lever S may be dexterously used together, the brake-lever being worked by one hand or by one operator, and the controlling-lever by the

other hand or another operator. First, the lever is turned to hasten the dead-wheel, and consequently to increase the speed of the engine until it revolves at a high velocity, then 5 the lever S is suddenly urged in the opposite direction to retard the dead-wheel and carry the weights B outward. At the same moment the brake is applied, and by its aid the dead-wheel is completely stopped. If this is done 10 with sufficient promptness the engine, by its momentum, turns the shaft C considerably ahead of the dead-wheel. This shifts the eccentric to its central or neutral point. If the momentum does not carry the parts actually 15 past that point and effect the reversing, the controlling-lever S completes the motion.

Modifications may be made in the forms and proportions without departing from the principle or sacrificing the advantages of the invention. There may be swiveling-joints on 20 the arms C' at the points where the rods H extend through, allowing the parts to better accommodate themselves to the changing angles of the rods H as the weights move outward 25 and inward. Instead of the hand-levers, other means may be employed for tightening the brake-strap P. Other forms of brake may be used. Parts of the invention may be used 30 without the whole. The brake-strap P and its operating means may be omitted, if desired. So, also, may the lever S and its connections be omitted, and the engine may be run 35 always at the rate for which the regulator is adjusted, and the motion may be reversed by stopping the engine and turning the dead-wheel by hand. I can arrange the stops A⁶ close together or employ the pins R² as the pins of the knuckles b which hinge the weights B to the 40 dead-wheel. Only one arm R' and pin or projection R² engaging with the dead-wheel may suffice. I have already shown how the momentum governor may be used alone with some 45 success. There may be other means than the cams A⁴ A⁵ and arms D² D³ for causing the outward movement of the weights to effect 50 the requisite changes of position of the eccentric on the shaft. A screw or screws may effect the changing and holding. The eccentric may be shifted across the shaft on straight guides. It can be capable of shifting only 55 from one extreme position to the neutral one without the capacity for reversing. I prefer the whole as shown.

I claim as my invention—

1. The steam-engine governor described, 55 having a heavy dead-wheel, A, unencumbered by the transmission of power, mounted loosely on the shaft C, in combination with a shifting eccentric, D, and operating mechanism 60 arranged, substantially as described, so as to cause the advance of the dead-wheel by its momentum and the drag by its inertia to shift the eccentric, substantially as herein specified.

2. In a steam-engine governor, the loosely-mounted dead-wheel A, with connections, as d' A⁴ A⁵, for shifting the point of cut-off by the inertia, in combination with weights B and means, as I, for urging such weights inward, so as to govern the speed by the joint influence 70 of sudden changes and centrifugal force, as herein specified.

3. In a steam-engine governor having a shifting eccentric and provisions, substantially as specified, for adjusting the point of cut-off 75 by the changes in speed, the arm C' on the shaft C, and the arm D' on the eccentric loosely connected by the pivot D⁴, in combination with each other and with provisions, as D² A⁴ D³ A⁵, for shifting the eccentric in a curved 80 path, substantially as herein specified.

4. In a steam-engine governor, a dead-wheel, A, capable of running faster or slower than the shaft C, weights B, and links E, arranged to allow of reversing, as herein specified. 85

5. In a steam-engine governor, a dead-wheel, A, shaft C, weights B, and links E, in combination with each other and with a brake, P, and operating means, as Q, arranged to serve 90 as herein specified.

6. A steam-engine governor having a shifting eccentric, D, means, as C' D' D⁴, for causing the eccentric to turn with the shaft, and independent means offering friction, as D² A⁴ 95 D³ A⁵, for changing the eccentricity of the eccentric, combined and arranged, as shown, so that the eccentric shall be held by friction at some points and be urged by the resistance of the valve alternately into positions of greater and less eccentricity at other points, all substantially as herein specified. 100

7. In a steam-engine, the loose, unloaded, or dead wheel A and connected shifting eccentric D, in combination with the loose hub 105 R, with arms R' and means, as w r X' W S, for urging the dead-wheel forward or backward, substantially as and for the purposes herein specified.

8. In a steam-engine governor having a 110 loose fly or dead wheel and connections therefrom to the shaft and to the mechanism for supplying steam to the engine, the combination, with such dead-wheel, of a brake, P, and means for operating it to retard the dead-wheel, and also of means, as S T R R', for positively turning the dead-wheel in one direction or the other relatively to the shaft, all substantially as and for the purposes herein specified. 115

In testimony whereof I have hereunto set my hand, at Indianapolis, Indiana, this 24th day of September, 1884, in the presence of two subscribing witnesses.
